UNITED STATES PATENT OFFICE.

WILLIAM F. MASON McCARTY, OF PLEASANTVILLE, NEW YORK, ASSIGNOR OF ONE-FOURTH TO GEORGE O. EATON, ONE-FOURTH TO THOMAS M. ACKEN, AND ONE-THIRTIETH TO ALEXANDER J. GUTTMAN, OF NEW YORK, N.Y.

METALLURGICAL FURNACE.

No. 901,363.

Specification of Letters Patent.

Patented Oct. 20, 1908.

Application filed December 14, 1907. Serial No. 406,498.

To all whom it may concern:

Be it known that I, WILLIAM F. MASON McCARTY, a citizen of the United States, residing at Pleasantville, in the county of 5 Westchester and State of New York, have invented certain new and useful Improvements in Metallurgical Furnaces, of which the following is a specification.

This invention relates to furnaces for the 10 reduction of ore and has particular reference to certain new and useful improvements in furnaces for producing and refining iron and steel.

An important object of my invention is 15 to provide a combined blast furnace and converter in which the process of treating iron and steel described and claimed in my copending application filed November 23rd, 1907; Serial Number 403,452, may be advantageously carried out.

In the drawing forming a part of this specification Figure 1 is a vertical sectional view of a blast furnace and converter embodying important features of my invention; Figs. 2, 3 and 4 are cross sectional views on lines 2—2, 3—3 and 4—4 of Fig. 1, and Fig. 5 is a vertical sectional view showing the preferred embodiment of my invention.

Referring to the drawings 1 designates a combined blast furnace and converter having the general shape of blast furnaces in common use and having its walls preferably formed of brick 2 with an inner lining 3 of fire clay and an outer casing 4 of iron.

The body portion or shaft 5 of the furnace is of the usual conical shape and terminates at its upper end in a filling opening 6 through which the products of combustion escape when the vacuum pump, hereinafter referred to, is not in operation. In order to close the furnace preliminary to the vacuum treatment the opening is provided with a removable cover 6' of suitable material. At 45 its lower portion the walls of the shaft converge downwardly to form the bosh 7 the lower end of which extends into the crucible 9 and is supported by radially disposed piers 10.

Twyers 11 are provided to supply air under pressure to the charge from a pipe 12 in communication with a blower or compressor (not shown). A second series of twyers 13 extend into the crucible as shown

and are arranged to supply superheated steam from a pipe 14 connected with a suitable source of supply (not shown).

Within the walls of the furnace are a series of vertical flues or ducts 15 which connect the space within the crucible 9 with the 60 interior of the shaft 5 near the upper portion thereof, by means of transverse passages 16. The flues or ducts 15 are in communication with a suitable outlet pipe or pipes 17 for conveying off gases and vapors 65 when the shaft is closed by the cover 6'. One of the flues 16 may be advantageously provided or connected with a safety or relief valve 18 comprising a pipe 19 having a cover or closure 20 normally held in position by 70 the spring 21 secured thereto and to the pin or bolt 22 passing through pipe 18 as shown. This safety or relief valve serves to instantly relieve any excess of pressure within the shaft 4 or crucible 9 caused, for example, by 75 an explosive expansion of steam in the metal, and thus prevents injury to the furnace itself or to the outlet pipe 17.

The lower end of the bosh is provided with an opening 23 through which metal may 80 pass to the crucible 9, which is provided with an outlet 24 normally closed by a fire clay plug 25.

In the use of my invention in carrying out the process hereinbefore referred to I 85 charge the furnace in the usual way, adding, however, to the charge about 106 pounds of sodium chlorid and 25 pounds of calcium chlorid to each ton of ore. The ore is reduced in the usual way, the cover 6 being removed, and air being blown in through twyers 11. When the ore is reduced the metal flows through the opening 23 into the crucible 9, and is here subjected to the action of superheated steam blown in through 95 twyers 13. By the action of the superheated steam upon the metal to which the chlorids of sodium and calcium have been added, the sulfur, phosphorus, cyanogen and other occluded gases are rendered susceptible of 100 ready removal by vacuum and air, in fact, in part removed by the action of the steam.

In order to complete the purification of the metal it is necessary to subject it to the action of a vacuum. This may be done by 105 removing it to a converter having means to subject it to the action of a vacuum or it may be done by closing the upper opening 5

of the furnace and withdrawing air by means of a suitable suction apparatus (not shown) through outlet openings 17.

In Fig. 5 I have illustrated a single apparatus in which the process, above referred to, can be carried out somewhat more advantageously than in the apparatus hereinbefore described.

The furnace is in all respects similar to that shown in Figs. 1 to 4, inclusive except that the outlet opening 24 connects directly with a vacuum chamber 26 to which the reduced metal may be conveyed without subjecting it to the action of air. In this case the outlet is controlled by a suitable slide valve or gate 24. The chamber 26 is preferably located beneath the furnace as shown, and is provided with a fire clay or fire brick lining 27.

20 A suction pipe 28 connects the upper part of the chamber with suitable cooling means as a coil or worm 29 disposed in a tank 30 normally filled with water as shown. The outlet 31 of the coil or worm is connected 25 with a suitable exhauster (not shown). The chamber 26 is provided with an outlet 32 normally closed by a fire clay plug 33.

In using the preferred embodiment of my invention in carrying out my process I treat 30 and reduce the charge as already described, injecting air through twyars 11 and after reduction blowing superheated steam through the metal in crucible 9. I may subject it then or during the treatment with the super- 35 heated steam to the influence of a vacuum by the action of an exhaust pump connected with outlet 17, or I may subject it alternately to the action of superheated steam and a vacuum.

40 By reason of the necessarily large dimensions of the chamber 5 it is practically impossible to secure a very high degree of vacuum therein. It is, therefore, ordinarily advisable, in practice, to convey the reduced 45 metal to the chamber 26 after it has been subjected to the treatment with superheated steam, and there subject it to a vacuum. Where, by reason of the character of the ore 50 or for other reasons it is deemed advisable 55 to subject the metal simultaneously or alternately to the action of steam and vacuum in the crucible 9, it is nevertheless advisable in practice to convey the metal to the chamber 26 and there subject it to a high degree of

vacuum before removing it to the molds.

By the interposition of suitable cooling means between the chamber 26 and the exhausting apparatus, the latter is protected from the heat of the gases and vapors re- 60 moved from the metal, and the less volatile of the latter are condensed before coming in contact with exhauster.

By my arrangement of the supporting piers 10 in the crucible, said piers serve to 65 separate and in a sense isolate portions of

the outer part of the metal in the crucible from each other and thus serve to localize the agitation or disturbance caused by the injection of superheated steam. Inasmuch as the steam is preferably injected into the metal midway between the piers the latter serve a useful purpose in preventing too violent agitation of the mass of metal in the crucible.

While I have described the operation of my furnace as used in carrying out the hereinbefore described process it is to be understood that it is not limited to such use but may be employed for any purpose for which it is found to be adapted.

Having thus described my invention, I claim:

1. A furnace of the character described comprising a body portion to receive the charge, a crucible to receive the reduced metal, means for supplying air under pressure to the charge in said body portion, means for supplying steam to the metal in the said crucible, said body portion being in communication with said crucible through an opening provided in the lower portion of the former and through a flue or duct leading from said crucible to the upper part of said body portion, substantially as described.

2. A furnace of the character described comprising a bosh and a crucible, the lower end of said bosh extending downward into the said crucible, said bosh being provided at its lower extremity with means of communication with said crucible and said furnace being provided with means of communication between said crucible, and the main portion of the furnace, above said bosh, substantially as described.

3. A furnace of the character described comprising a bosh and a crucible, said bosh extending downward into said crucible below the upper edge of the sides thereof, said crucible being in communication with said bosh through the lower end thereof, substantially as described.

4. A furnace of the character described comprising a crucible, means for supplying steam to different portions of said crucible and means for localizing the agitation or disturbance of metal in said crucible produced by the injection of said steam, substantially as described.

5. A furnace of the character described comprising a crucible having partitions therein adapted to separate portions of the contents from each other and means for supplying steam under pressure to said portions, substantially as described.

6. A furnace of the character described comprising a bosh and a crucible, the lower end of said bosh extending downward into the said crucible, and supported in such position by piers forming partition walls in

said crucible and means of communication between said bosh and crucible, substantially as described.

7. A furnace of the character described having a body portion comprising a shaft and a bosh, means for supplying air under pressure to said body portion adjacent the said bosh, a crucible located beneath said bosh and in communication therewith, means for supplying superheated steam to said crucible and means of communication between said crucible and said stack said means of communication comprising a flue or duct provided within the walls of said furnace, substantially as described.

8. A furnace of the character described comprising a body portion and a crucible, the walls of said body portion being provided with a flue or duct connecting the upper part thereof with said crucible, an outlet pipe in communication with said flue or duct, means for supplying air under pressure to said body portion and means for supplying superheated steam to said crucible, substantially as described.

9. A furnace of the character described comprising a body portion to receive the charge, a crucible to receive the reduced metal, means for supplying superheated steam to the metal in said crucible and vacuum-producing means suitably connected with said crucible and adapted to withdraw air therefrom, substantially as described.

10. A furnace of the character described comprising a body portion to receive the charge, a crucible to receive the reduced metal, means for supplying air under pressure to the charge in said body portion, means for supplying steam to the metal in the said crucible and vacuum-producing means suitably connected with said body portion and crucible and adapted to withdraw air therefrom, substantially as described.

11. An apparatus of the character described comprising a body portion to receive the charge, a crucible to receive the reduced metal, means for supplying air

under pressure to the charge in said body portion, means for supplying steam to the metal in said crucible and a chamber adapted to be thrown into communication with said crucible, said chamber being provided with means for exhausting air therefrom, substantially as described.

12. An apparatus of the character described comprising a body portion to receive the charge, a crucible located beneath said body portion and in communication therewith through an opening provided in the lower part of the latter and through a flue or duct leading from said crucible to the upper part of said body portion, and a chamber having a valve controlled connection with said crucible, said chamber being provided with means for exhausting air therefrom, substantially as described.

13. An apparatus of the character described comprising a body portion to receive the charge, a crucible to receive the reduced metal, means for supplying steam to the metal in the said crucible, means for exhausting air from said crucible and a chamber having a valve controlled connection with said crucible and adapted to receive metal therefrom, said chamber being provided with means to exhaust air therefrom, substantially as described.

14. An apparatus of the character described comprising a body portion to receive the charge, a crucible to receive reduced metal, means for supplying air under pressure to the charge in said body portion, means for supplying steam to the metal in said crucible, means for exhausting air from said crucible and a chamber having a valve controlled connection with said crucible and adapted to receive metal therefrom said chamber being provided with means for withdrawing air therefrom, substantially as described.

In testimony whereof I affix my signature in presence of two witnesses.

WILLIAM F. MASON McCARTY.
